(57) **CLAIM**

The ornamental design for a LED light base, as shown and described.

DESCRIPTION

FIG. 1 is a perspective view of a LED light base showing my new design;

FIG. 2 is a top view of the LED light base shown in FIG. 1;

FIG. 3 is a bottom view of the LED light base shown in FIG.

1;

FIG. 4 is a left side view of the LED light base shown in FIG.

1; and,

FIG. 5 is a right side view of the LED light base shown in FIG.

1.

1 Claim, 5 Drawing Sheets
